Application August 23, 1950, Serial No. 181,018

12 Claims. (Cl. 103—38)

1

This invention relates to pumps, and more particularly to pumps designed to measure a predetermined volume of liquid during each stroke or cycle of the pump.

This invention is particularly adapted for use with corrosive fluids or those containing gritty particles, tending to corrode or cut out the interior walls of the working parts of an ordinary pump, as well as with fluids which would become contaminated if allowed to contact the interior surfaces of an ordinary pump.

One object of the invention is to provide an improved pump having a more practical and efficient type of construction, for accurately measuring and pumping a predetermined volume of fluid during each stroke or cycle of the pump.

Another object is to provide a pump of the above character which has means for precisely adjusting and regulating the volume of fluid measured and pumped.

Another object of the invention is to provide a pump having the above advantages and which is particularly adapted for use with corrosive fluids, fluids containing gritty particles or fluids which would be contaminated if allowed to contact the interior surfaces of an ordinary pump.

Another object of the invention is to provide a pump of the above character having a minimum clearance volume, the proportions of which remain constant regardless of the length of the pumping stroke thereby insuring a uniform volume of fluid pumped per stroke and providing an improved pump construction adapted for pumping liquified gases which, at given operating temperatures, may be supplied at pressures closer to their vapor pressures than was heretofore possible.

A further object of the invention is to provide a pump having the above advantages and which is compact in size, flexible in operation and capable of producing a high pressure in the fluid to be pumped.

Still a further object of the invention is to provide a pump having the above advantages in a more practical and efficient type of construction capable of being readily manufactured and of operating in an accurate and reliable manner.

To these and other ends the invention resides in certain improvements and combinations of parts, all as will be hereafter more fully described, the novel features being pointed out in the claims at the end of the specification.

In the drawings:

Fig. 1 is an elevation view of a pumping and measuring mechanism embodying the present in-

2

vention showing the location of, and the connections between, the measuring pump, the adjustable regulating valve mechanism and the motor driven actuator;

Fig. 2 is a fragmentary top plan view of the pumping and measuring mechanism as shown in Fig. 1;

Fig. 3 is an elevation view, partly in section, of the actuator showing the construction of the hollow piston and movable cylinder;

Fig. 4 is a side elevation view of the actuator as shown in Fig. 3 showing the means for connecting the cylinder to a motor driven eccentric;

Fig. 5 is an enlarged elevation view of the measuring pump and certain of its connecting means;

Fig. 6 is a sectional elevation substantially on line 6—6 in Fig. 5 showing the internal construction of the measuring head and the location of the flexible separating diaphragm;

Fig. 7 is an enlarged sectional elevation taken through the center of the adjustable regulating means parallel with the longitudinal axis thereof and showing the free piston in position for uncovering the bypass port, and

Fig. 8 is a sectional view substantially on the line 8—8 of Fig. 7 showing the location of the bypass port.

The preferred form of the invention, herein disclosed by way of illustration, comprises a motor driven actuator or pump 11 (Fig. 1) for producing an actuating fluid flow alternately in opposite directions, a measuring pump 12 adapted to be actuated by said first fluid for pumping a second fluid in measured quantities and an adjustable regulating means 13 interposed between and connected to said actuator and said measuring pump by connecting pipes 14 and 15, respectively (Fig. 1).

The actuator or pump 11 comprises, preferably, an elongated piston 16 (Figs. 3 and 4) mounted for rocking movement and received in a cylinder 17 having a rocking and reciprocating movement for pumping cooperation with the piston. The piston is fixed to and extends upwardly from the upper end of a rocking yoke 18 having depending arms 19 provided with openings seated on the ends of a short shaft 20 mounted to rock in a self-aligning bearing 21 (Fig. 4). A set screw 22 serves to fix the yoke to the shaft. To provide the piston with efficient packing or sealing means, its upper end is reduced as at 24 (Fig. 3) to form a shoulder 25. The reduced portion 24 carries two packing rings in the form 55 of cup-shaped gaskets, 26 and 27, preferably of

leather or other suitable material, and cupped upwardly toward the free or pressure side of the cylinder, to provide an efficient sealing fit in the cylinder with low frictional resistance, as well understood in the art. Ring 27 is spaced upwardly along piston 16 from ring 26 by a metallic cup follower 28. A second cup follower 29 is inserted between upper ring 27 and the end of the piston 16. Nut 31, threadedly secured to the upper end of piston 16, engages the upper surface of cup follower 29 and holds the above sealing rings and cup followers firmly in place as shown in Fig. 3.

Piston 16 has a hollow passageway 32 (Fig. 3) extending longitudinally from the upper or free end thereof into the upper portion of piston yoke 18 where said passageway is intersected by a transversely extending hollow passageway 33 (Figs. 3 and 4) which extends inwardly from outer face 34 of piston yoke 18. Passageways 32 and 33 thus form a continuous path through which fluid is forced when the cylinder is reciprocated by means hereafter described. The outer portion of passageway 33 is threaded for connection to said conduit 14.

When cylinder 17 is in its lowermost position as shown in Figs. 3 and 4, the upper end 35 (Fig. 3) of bore 23 of the cylinder is slightly above the upper end 36 of piston 16 and thereby provides a small clearance volume which is intersected by two transversely extending bores 37 and 38 which are adapted to be connected to a vacuum relief inlet valve 39 and a pressure relief valve 41, respectively, the functions and operation of which will be hereafter more fully explained.

The upper end of cylinder 17 is fixed to the lower end of a connecting rod 42 by a bolt 43 (Figs. 3 and 4). Connecting rod 42 has its upper or opposite end formed with a bearing 44 receiving a short shaft or trunnion 45 which is eccentrically mounted on an eccentric disk 46 (Fig. 4). Connecting rod 42 is held in place on trunnion 45 by a bolt 47 and washer 48. Disk 46 is fixed, as by a key 49 on the shaft 50 of an electric motor 51 (Fig. 1) which supplies the power for rotating said eccentric disk and thereby operating the actuating pump.

The actuating pump 11 is adapted to be secured either to a support 53 (Fig. 1) located within a tank 54 containing the oil or other actuating fluid, or directly to the bottom 55 of the tank and is connected by conduit 14, to an adjustable regulating valve which will hereafter be described.

It is intended that the upper surface of the actuating or pumping fluid extend above inlet valve 39 and release valve 41, as shown at 56 (Fig. 1) to minimize the possibility of air being drawn into the system and, to insure an ample supply of fluid under all adjustments, the actuator pumps a greater volume of fluid per stroke than is required for the operation of the regulating valve 13 and measuring pump 12. The excess fluid is allowed to escape through pressure relief valve 41 into tank 54. A second pressure relief valve 60 (Fig. 1) having a return conduit 70 emptying into tank 54, is inserted between regulating valve 13 and measuring pump 12, as hereafter more fully described.

Thus, it will be seen that when electric power is supplied to motor 51, eccentric disk 46 is rotated and cylinder 17 is caused to reciprocate along piston 16. As the cylinder moves upwardly from its lowermost position as shown in

Fig. 3, reduced pressure is formed in the cylinder which draws fluid from the regulating valve 13 through conduit 14 and chambers 33 and 32. As the above volume of fluid is not sufficient to relieve the reduced pressure within said cylinder, atmospheric pressure on fluid in the tank operates the normally closed, spring actuated, vacuum relief inlet valve 39, which opens and allows the fluid to flow into the cylinder and keep it filled. As the cylinder reverses direction and moves downwardly to the position as shown in Fig. 3, valve 39 closes and the fluid is forced downwardly and outwardly through passageways 32 and 33 and through conduit 14 into regulating valve 13. Thus during each stroke or cycle of the actuating pump, the fluid in conduit 14 is moved alternately in opposite directions under sub- and super-atmospheric pressure, respectively.

The actuating fluid, under the pulsating pressure described above, passes through regulating valve 13, by means which will be hereafter described and is carried by conduit 15 to measuring pump 12 for actuating the same.

Measuring pump 12 comprises a pair of cylindrical plates 57 and 58, of corrosion resisting material, as for example, stainless steel and having a substantial thickness as shown in Fig. 6 and thus are adapted to withstand high fluid pressures. Plates 57 and 58 are formed with transversely extending bores 59 and 61, respectively. Bore 59 is closed at one end by a plug 62 and has attached to its opposite end a nipple 63 which is adapted to receive conduit 15 for transmitting the actuating fluid into said chamber. Plate 57 has formed therein a series of holes 64 (Figs. 5 and 6) which extend transversely to the longitudinal axis of bore 59 and connect it with the interface 65 of the plate. Plate 58 has a similarly formed series of holes 66 which connect its interface 67 with bore 61. Plates 57 and 58 are adapted to be securely fastened together by studs 68 and nuts 69 with interfaces 65 and 67, respectively, substantially in contact with one another, as shown in Fig. 6.

A thin flexible diaphragm 71 preferably of stainless steel, rubber or an inert plastic, is securely fastened between interfaces 65 and 67 and thus forms a liquid-proof seal between bores 59 and 61 and their series of holes 64 and 66. Interfaces 65 and 67 are concavely recessed inwardly adjacent the center portions thereof as at 72 and 73, respectively, and thus provide a space divided into two separate chambers by the movable wall or flexible diaphragm 71. This partitioning diaphragm is adapted to be moved in response to the pulsation of the actuating fluid passing through bore 59 and holes 64, into the space between the diaphragm and the recessed interface of plate 57, such movement of the diaphragm serving to alternately enlarge and contract the chamber between the opposite side of the diaphragm and the interface of plate 58 to effect pumping of a second fluid to be measured as hereafter more fully described.

Plate 58 has connected therewith adjacent each end of bore 61 a double ball check valve assembly, indicated generally by the numerals 74 and 75, respectively, for insuring unidirectional flow of fluid through said chamber in response to the movement of the diaphragm 71. As these valve assemblies are of similar construction a description of one will be sufficient. Thus, the lower or inlet valve assembly 75 (Fig. 6) comprises a collar 76 attached to plate 58. A

pair of cup-shaped valve blocks 77 and 78 and ball valves 79 and 81 are inserted within collar 76. A flanged nipple 82 abutting the outermost valve block is securely held in place by a nut 83 screwed into the outer end of collar 76. Valve blocks 77 and 78 are formed with valve seats having sharp edges which insure proper closing of the ball valves. A drain cock 84 is attached to collar 76, as shown in Fig. 6, to allow removal of any fluid which may leak out around the valve assembly within collar 76.

The lower valve assembly is adapted to allow fluid to move into chamber 61 but to prevent the fluid from moving out of the chamber through the valve assembly. The upper or outlet valve assembly 74 is similar to the inlet valve assembly but is arranged to allow fluid to pass from chamber 61 out through valve assembly 74 and to prevent fluid from moving through the valve assembly into said chamber. Thus, it will be seen that when nipple 82 leading from the inlet valve assembly is attached to a fluid supply, the reciprocating movement of flexible diaphragm 71 alternately creates a super- and sub-atmospheric pressure region in bore 61 and alternately draws fluid into said bore through inlet valve assembly 75 and discharges the fluid through the outlet valve assembly 74.

The movement of diaphragm 71 to the right is restricted by recessed portion 73 of interface 67 and to the left by recessed portion 72 of interface 65. Each time the diaphragm 71 moves from a position in contact with recessed portion 73 to a position in contact with recessed portion 72, and back again to its initial position, it has displaced a constant volume. Thus, as the diaphragm is caused to reciprocate in response to the pulsations or pressure changes in the actuating fluid, pump 12 measures a constant volume of fluid for each cycle of movement of the flexible diaphragm.

My invention also comprises a novel regulating means 13, interposed between actuator 11 and measuring pump 12, for accurately regulating and controlling, per cycle, the volume of a second fluid measured by pump 12. This regulating means, as presently more fully described, restricts the movement of diaphragm 71 to the left, as seen in Fig. 6, and thereby limits the volume per cycle of fluid drawn into bore 61 and its connected diaphragm chamber.

Regulating means 13 comprises basically a cylinder, shown generally at 85 (Fig. 7), and a closely fitting free piston 86 which is adapted to move in opposite directions in response to the pulsations of the actuating fluid. Cylinder 85 comprises a body section 87 (Fig. 7) which has grooves at opposite ends thereof containing split rings 88 and flanges 89 for connecting said body portion to end members 91 and 92, respectively. Said flanges are fastened to said end members by bolts 93. A gasket 94 located at each end of cylinder body section 87 insures a tight seal between said body section and end members 91 and 92. End member 91 has a threaded opening 95 adapted to be connected to conduit 14 for transmitting the actuating fluid to and from said cylinder. End member 92 has a bore 96 extending from its inner surface partially therethrough and forming at the outer end thereof a shoulder 97. A smaller counterbore 98 connects said bore 96 with a threaded opening 99 which is adapted to be connected to conduit 15. Bore 96 is slightly smaller in diameter than the bore of cylinder 87 and thus forms a stop for restricting the

movement in one direction of piston 86. A bore 101 extends inwardly from the right hand end of piston 86, as seen in Fig. 7, partially through said piston. A coil compression spring 102 is inserted in bore 101 and has one end thereof in contact with the inner end of said bore and the opposite end thereof in contact with shoulder 97 for moving the piston to the left as viewed in Fig. 7.

Body portion 87 is provided with a bypass port 103 (Figs. 7 and 8) adjacent the right hand end thereof as viewed in Fig. 7, which allows "make-up" actuating fluid to flow from cylinder 87 around the piston and out through outlet 99 and conduit 15 to the measuring pump bore 59, to keep its passageways filled. However, bypass port 103 is of limited extent so that it is open only when piston 86 is adjacent its right hand position as shown in Fig. 7.

Thus, as the actuating fluid enters cylinder 87 under super-atmospheric pressure it causes piston 86 to move to the right, as seen in Fig. 7, thereby forcing the actuating fluid to flow through outlet 99 and conduit 15 to the measuring pump where it moves diaphragm 71 to the right as viewed in Fig. 6.

If at any point during this downward stroke of actuator cylinder 17 the pressure of the actuating fluid exceeds a predetermined amount, relief valve 60 opens to relieve said excessive pressure and allows the excess fluid to return to tank 54 by return conduit 70.

Valve 60 not only relieves the actuating system of the excess fluid per stroke, as pointed out above, but as it is located at the highest point in the actuating fluid system, as for example, between nipple 63 and conduit 15, it also bleeds any air or gas bubbles entrapped in the actuating fluid. It has been found desirable when pumping a second fluid at a given pressure to set the actuating fluid pressure relief valves 60 and 41 to open at pressures slightly greater than the above given pressures. In normal operation, therefore, when pumping the second fluid at a given pressure, as for example, 1000 p. s. i., the actuating fluid moves diaphragm 71 into contact with recessed portion 73 after which the pressure of the actuating fluid continues to build up until it reaches a predetermined amount, as for example, 1100 p. s. i., at which point valve 60 opens. Thus, once every cycle, valve 60 opens to allow a small amount of actuating fluid and entrapped gas bubbles to escape. If valve 60 fails to operate, or for any reason the pressure in the actuator exceeds a second predetermined amount, as for example, 1200 p. s. i., relief valve 41 opens allowing the excess fluid to escape into container 54 thereby protecting the actuating fluid system.

When actuator cylinder 17 moves upwardly, creating a region of sub-atmospheric pressure in said actuator, the actuating fluid is drawn out of cylinder 87 thereby drawing piston 86 to the left, assisted initially by spring 102. More specifically, this movement of piston 86 quickly closes bypass port 103 and shuts off the flow of the actuating fluid therethrough. However, as piston 86 moves to the left, it creates in bores 98 and 99 a reduced pressure which withdraws the actuating fluid from measuring pump bore 59 and its connected diaphragm chambers. The farther piston 86 moves to the left, as viewed in Fig. 7, the greater the reduction in pressure and the greater the amount of fluid drawn out of bore 59. This increases the distance through which diaphragm 71 is moved away from recessed

portion 73 towards the opposite recessed portion 72 and simultaneously increases the volume of fluid drawn in through bore 61 during the movement of said diaphragm. It is evident that if piston 86 is allowed to travel through a sufficient distance, diaphragm 71 will contact recessed portion 72 thereby drawing the maximum volume of fluid into bore 61 and its connected diaphragm chambers. Conversely, if the leftward movement of piston 86 is decreased, the amount of actuating fluid drawn out of bore 59 will be less and diaphragm 71 will move through a correspondingly smaller distance thereby drawing a smaller amount of fluid into measuring bore 61.

As actuator cylinder 17 moves downwardly the actuating fluid is again under super-atmospheric pressure and piston 86 moves to the right to the position as shown in Fig. 7, thereby forcing fluid into chamber 59 and moving diaphragm 71 in the opposite direction until it strikes against recessed portion 73. Thus, limiting the leftward movement of piston 86, as viewed in Fig. 7, restricts the movement of flexible diaphragm 71 towards recessed portion 72 and thus reduces the volume of fluid per cycle drawn into and pumped out of bore 61.

The means for restricting the movement of piston 86 comprises a variably adjustable stop rod 104 (Fig. 7) which passes longitudinally through an extension 105 of end member 91. A manually rotatable cap 106, bored at the outer end thereof to allow the outer end of rod 104 to extend therethrough, is threadedly engaged with extension 105. A pin or set screw 107 secures said rod to said cap, so that as cap 106 is rotated to screw it on extension 105, rod 104 is moved longitudinally through said extension and into cylinder 87. A collar 108 is secured by set screw 109 to rod 104 inside the cylinder and provides a means for limiting the outward movement of rod 104 as shown in Fig. 7. By rotating cap 106 as described, rod 104 is moved inwardly as far as desired towards the right end of cylinder 87 to arrest and limit the leftward movement of piston 86, for the purposes pointed out above. Extension 105 has adjacent the outer end thereof two packing rings 111 to prevent leakage of actuating fluid along rod 104. A nut 112 is securely fastened to the outermost end of rod 104 as shown in Fig. 7 and provides a means for the attachment of a wrench or other suitable tool.

It will be seen that when the actuating fluid is under super-atmospheric pressure, piston 86 is moved into contact with end portion 92 and the actuating fluid passes into the measuring pump, thereby moving diaphragm 71 to the right until stopped by recessed portion 73. As the actuating fluid is thereafter subjected to sub-atmospheric pressure, piston 86 is drawn to the left until it engages stop rod 104. As pointed out above, the greater the leftward movement of piston 86, the greater is the leftward movement of diaphragm 71 and the greater is the volume of fluid drawn into the measuring pump. When the actuating fluid is again under superatmospheric pressure, the above cycle is repeated causing diaphragm 71 to move again to the right to expel through outlet valve 74 the fluid which was previously drawn into measuring bore 61 through inlet valve 75.

It is apparent from the above description that the invention supplies a positive displacement diaphragm pump for accurately metering and pumping liquids under pressure. The spring ten-

sion at which the automatic relief intake and discharge valves 39 and 60 operate is so determined as to insure the full desired operating stroke of the regulating piston 86 before the valves operate to relieve the actuating pump 11. That is, on the upward or suction stroke of cylinder 17, the reduced pressure moves piston 86 to the left in Fig. 7 until arrested by stop means, such as the end of the rod 104, after which the relief inlet valve 39 opens to supply additional oil from the reservoir to the pump 11, depending in quantity on the length of stroke of piston 86 as controlled by stop rod 104. This suction stroke first withdraws the oil or other actuating fluid from the left hand side of the diaphragm (Fig. 6) to move the diaphragm toward the left to a distance controlled by the setting of the stop rod 104 and thus, movement of the diaphragm draws fluid to be pumped past the lower check valves, 79 and 81, to fill the chamber and connections at the other side of the diaphragm.

During the downward or pressure stroke of cylinder 17, the oil pressure forces piston 86 toward the right (Fig. 7), thereby forcing the liquid at the other end of the piston back into the diaphragm chamber, to force the diaphragm against the concave face 73 of plate 58. This forces the fluid to be pumped under positive pressure from this diaphragm chamber through bore 61 and the upper or outlet check valves. During this stroke of piston 86, it compresses spring 102 and uncovers port 103 to insure a full supply of the actuating fluid to the diaphragm chamber and full pressure on the diaphragm to complete its pumping pressure stroke, after which relief discharge valve 60 opens to permit excess oil to flow from the actuating fluid system into the reservoir. If for any reason valve 60 fails to operate or fails to reduce the pressure of the actuating fluid, a second pressure relief valve 41 opens, thereby permitting the actuating fluid to escape from cylinder 17 into container 54.

On the subsequent suction stroke, spring 102 quickly initiates and assists the return movement of piston 86. Such movements of regulating piston 86 in opposite directions cause the pumping diaphragm 71 to move in direct volumetric relation and since the diaphragm, at the end of the pressure stroke, is hydraulically forced to conform to the machined concavity of plate 58, the liquid volume held between the inlet and outlet check valves of the metering pump, hereafter referred to as the clearance volume, is a minimum volume and remains constant regardless of the length of stroke of the pump. Stop rod 104 may be precisely adjusted for controlling said stroke length by screwing the cap 106 on the extension 105, thus providing an adjustment of substantially micrometric fineness and precision.

The above construction in which the clearance volume is always the same and is determined solely by the engagement of diaphragm 71 with recessed concavity 73, insures greater accuracy and uniformity of fluid pumped per cycle because the compressibility of the actuating fluid does not affect the position of the diaphragm at the end of the discharge stroke. Thus, the accuracy of the above pump does not depend on the often inexact balancing of hydraulic pressures on opposite sides of the pumping diaphragm as was commonly the case in the prior constructions.

Maintaining the clearance volume at minimum constant proportions means that regardless of the length of the pumping stroke, my improved pump has a higher compression ratio (i. e., a

higher ratio between the total volume and the clearance volume) than most pumps of similar construction. A further advantage of this construction is that my pump will operate satisfactorily with liquefied gases which may be supplied at pressures closer to their vapor pressures, for their corresponding operating temperatures, than was heretofore possible with pumps of this type.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. Conducting means for containing a fluid, an actuating fluid therein, an actuator for pumping said fluid alternately in opposite directions, a fluid measuring pump operated by said actuating fluid for pumping a predetermined volume of a second fluid, said measuring pump having a wall portion movable alternately in opposite directions by said actuating fluid for pumping said second fluid, and a variably adjustable regulating means connected between said actuator and said measuring pump in series hydraulically therewith for regulating the flow of said actuating fluid from said measuring pump for restricting the movement of said wall portion in one direction for controlling the amount of said second fluid pumped by said measuring pump.

2. Conducting means for containing a fluid, an actuating fluid therein, an actuator for pumping said fluid alternately in opposite directions, a fluid measuring pump operated by said actuating fluid for pumping a predetermined volume of a second fluid, said measuring pump having a wall portion movable alternately in opposite directions by said actuating fluid for pumping said second fluid, and a variably adjustable regulating means connected between said actuator and said measuring pump in series hydraulically therewith, said regulating means comprising a cylinder and piston therein movable in opposite directions by said actuating fluid during each cycle of said measuring pump for regulating the application of said actuating fluid to said measuring pump for insuring actuation of said wall to the limit of movement thereof in the direction for pumping said second fluid and maintaining a uniform clearance volume in the side of the measuring pump through which said second fluid is being pumped regardless of the volume of said second fluid being pumped.

3. Conducting means for containing a fluid, an actuating fluid therein, an actuator for pumping said fluid alternately in opposite directions, a fluid measuring pump operated by said actuating fluid for pumping a predetermined volume of a second fluid, said measuring pump having a wall portion movable alternately in opposite directions by said actuating fluid for pumping said second fluid, and a variably adjustable regulating means connected between said actuator and said measuring pump in series hydraulically therewith, said regulating means comprising a cylinder containing a piston movable in opposite directions by said actuating fluid during each cycle of said measuring pump for controlling the application of said actuating fluid to said measur-

ing pump, and adjustable stop means on said cylinder for limiting the movement of the piston in one direction for controlling the flow of said actuating fluid from said measuring pump for regulating the volume of said second fluid pumped by said measuring pump.

4. Conducting means for containing a fluid, an actuating fluid therein, an actuator for pumping said fluid alternately in opposite directions, a fluid measuring pump operated by said actuating fluid for pumping a predetermined volume of a second fluid, said measuring pump having spaced immovable wall portions and a wall portion therebetween movable alternately in opposite directions by said actuating fluid for pumping said second fluid, and a variably adjustable regulating means connected between said actuator and said measuring pump in series hydraulically therewith, said regulating means comprising a cylinder containing a piston movable in one direction for allowing application of the full pressure of said actuating fluid to one side of said movable wall portion for insuring actuation of said movable wall portion against one of said fixed wall portions in the direction for pumping said second fluid for maintaining a uniform clearance volume in the side of the measuring pump through which said second fluid is pumped at the end of the pumping stroke of said measuring pump, regardless of the volume of said second fluid being pumped, adjustable stop means on said cylinder engaging said piston for limiting the movement thereof in the opposite direction for controlling the flow of said actuating fluid from said measuring pump for regulating the volume of said second fluid pumped by said movable wall portion.

5. Conducting means for containing a fluid, an actuating fluid therein, an actuator for pumping said fluid alternately in opposite directions, a fluid measuring pump operated by said actuating fluid for pumping a predetermined volume of a second fluid, said measuring pump having spaced immovable wall portions and a wall portion therebetween movable alternately in opposite directions into contact with said immovable wall portions by said actuating fluid for pumping said second fluid, a variably adjustable regulating means connected between said actuator and said measuring pump in series hydraulically therewith, said regulating means comprising a cylinder containing a piston movable in opposite directions for regulating the application of said actuating fluid to said measuring pump, a bypass port, means for opening said port at the end of the movement of said piston in one direction for allowing application of the full pressure of said actuating fluid to one side of said movable wall portion for insuring actuation of said movable wall portion against one of said fixed wall portions in the direction for pumping said second fluid for maintaining a uniform clearance volume on the opposite side of said movable wall portion at the end of the pumping stroke of said measuring pump regardless of the volume of said second fluid being pumped, and adjustable stop means on said cylinder engaging said piston for limiting the movement thereof in the opposite direction for restricting the flow of said actuating fluid from said measuring pump for controlling the actuation of said wall portion in a direction opposite to said pumping direction for limiting the volume of said second fluid pumped by said movable wall portion.

6. Conducting means for containing a fluid, an

11

actuating fluid therein, an actuator for pumping said fluid alternately in opposite directions, a fluid measuring pump operated by said actuating fluid for pumping a predetermined volume of a second fluid, said measuring pump having spaced immovable wall portions and a wall portion therebetween movable alternately in opposite directions into contact with said immovable wall portions by said actuating fluid for pumping said second fluid, a variably adjustable regulating means connected between said actuator and said measuring pump in series hydraulically therewith, said regulating means comprising a cylinder containing a piston movable in opposite directions for regulating the application of said actuating fluid to said measuring pump, a by-pass port in said cylinder adjacent one end thereof and arranged to be opened by said piston at the end of its movement in one direction for allowing application of the full pressure of said actuating fluid to one side of said movable wall portion for insuring actuation of said movable wall portion against one of said fixed wall portions in the direction for pumping said second fluid and maintaining a uniform clearance volume on the opposite side of said movable wall portion at the end of the pumping stroke of said measuring pump regardless of the volume of said second fluid being pumped, adjustable stop means on said cylinder engaging said piston for limiting the movement thereof in the opposite direction for restricting the flow of said actuating fluid from said measuring pump for controlling the actuation of said wall portion in a direction opposite to said pumping direction for limiting the volume of said second fluid drawn into and subsequently pumped by said movable wall portion, and spring means in said cylinder urging said piston against said stop means.

7. Conducting means for containing a fluid, an actuating fluid therein, an actuator for pumping said fluid alternately in opposite directions, a fluid measuring pump operated by said actuating fluid for pumping a predetermined volume of a second fluid, said measuring pump having spaced immovable wall portions and a wall portion therebetween movable alternately in opposite directions into contact with said immovable wall portions by said actuating fluid for pumping said second fluid, a variably adjustable regulating means connected between said actuator and said measuring pump in series hydraulically therewith, said regulating means comprising a cylinder containing a piston movable in opposite directions for regulating the application of said actuating fluid to said measuring pump, a by-pass port in said cylinder comprising a longitudinally-extending groove therein adjacent one end thereof, said groove being longer than said piston and positioned to be uncovered by said piston at the end of its movement in one direction for allowing application of the full pressure of the actuating fluid to flow through said port and around said piston against one side of said movable wall portion for insuring actuation of said movable wall portion against one of said fixed wall portions in the direction for pumping said second fluid and maintaining a uniform clearance volume on the opposite side of said movable wall portion at the end of the pumping stroke of said measuring pump regardless of the volume of said second fluid being pumped, adjustable stop means on said cylinder engaging said piston for limiting the movement thereof in the opposite direction for restricting the flow of said actuating fluid from

12

said measuring pump for controlling the actuation of said wall portion in a direction opposite to said pumping direction for limiting the volume of said second fluid drawn into and subsequently pumped by said movable wall portion, and spring means in said cylinder urging said piston against said stop means.

8. Conducting means for containing a fluid, an actuating fluid therein, an actuator for pumping said fluid alternately in opposite directions, a fluid measuring pump operated by said actuating fluid for pumping a predetermined volume of a second fluid, said measuring pump comprising spaced immovable wall portions having therebetween a movable wall portion forming two chambers in said pump, said movable wall portion being movable alternately in opposite directions by the pressure of said actuating fluid in one of said chambers for pumping said second fluid through the other of said chambers, and a variably adjustable regulating means connected between said actuator and with one of said chambers in series hydraulically therewith for regulating the application of said actuating fluid from said chamber for controlling the volume of said second fluid drawn into and subsequently pumped by the other of said chambers.

9. Conducting means for containing a fluid, an actuating fluid therein, an actuator for pumping said fluid alternately in opposite directions, a fluid measuring pump operated by said actuating fluid for pumping a predetermined volume of a second fluid, said measuring pump comprising spaced immovable wall portions having therebetween a movable wall portion forming two chambers in said pump, said movable wall portion being movable alternately in opposite directions by the pressure of said actuating fluid in one of said chambers for pumping said second fluid, and a variably adjustable regulating means connected between said actuator and said one of said chambers in series hydraulically therewith for regulating the flow of said actuating fluid from said chamber for restricting the movement of said flexible diaphragm in one direction for controlling the volume of said second fluid drawn into and subsequently pumped by the other of said chambers.

10. Conducting means for containing a fluid, an actuating fluid therein, an actuator for pumping said fluid alternately in opposite directions, a fluid measuring pump operated by said actuating fluid for pumping a predetermined volume of a second fluid, said measuring pump comprising spaced immovable wall portions having therebetween a movable wall portion forming two chambers in said pump, said movable wall portion being movable alternately in opposite directions by said actuating fluid for pumping said second fluid, conducting means connected with one of said chambers and provided with automatic valve means for maintaining unidirectional flow of said second fluid through said chamber, and a variably adjustable regulating means connected between said actuator and the other of said chambers in series hydraulically therewith for regulating the flow of said actuating fluid from said chamber for restricting the movement of said flexible diaphragm in one direction for controlling the volume of said second fluid drawn into and pumped by the first mentioned chamber.

11. Conducting means for containing a fluid, an actuating fluid therein, an actuator for pumping said fluid alternately in opposite directions, a fluid measuring pump operated by said actuat-

13

ing fluid for pumping a second fluid, a variably adjustable regulating means connected between said measuring pump and said actuator in series hydraulically therewith for regulating the application of said actuating fluid to said measuring pump alternately in opposite directions for actuating said pump to supply said second fluid at a predetermined rate, and pressure relief means operated by said actuating fluid for limiting the maximum pressure exerted by said fluid and for 10 bleeding entrapped gas bubbles from said fluid.

12. Conducting means for containing a fluid, an actuating fluid therein, an actuator for pumping said fluid alternately in opposite directions, a fluid measuring pump operated by said actuating fluid for pumping a predetermined volume of a second fluid, said measuring pump having a wall portion movable alternately in opposite directions by said actuating fluid for pumping said second fluid, a variably adjustable regulating means connected between said actuator and said measuring pump in series hydraulically therewith 15 20

14

for regulating the flow of said actuating fluid from said measuring pump for restricting the movement of said wall portion in one direction for controlling the volume of said second fluid pumped by said measuring pump, and pressure relief means operated by said actuating fluid for limiting the maximum pressure exerted by said fluid and for bleeding entrapped gas bubbles from said fluid.
